RELEASABLE DRIVING MEANS FOR CONNECTING DRIVING AND DRIVEN MEMBERS

William Russell Redd, Western Springs, Ill., assignor to Wm. Wrigley Jr. Company, Chicago, Ill., a corporation of Delaware

Application February 11, 1938, Serial No. 190,130

7 Claims. (Cl. 74—125.5)

This invention relates to a releasable driving means for connecting a driving member and a driven member. It is of special advantage for use in and is herein illustrated as applied to mechanism for feeding and severing a continuous web bearing in succession equally spaced labels or markings to be cut into lengths in such relation to such labels or markings, that when wrapped about the packages for which they are designed, the labels or markings will be disposed in proper register with the faces of the package upon which they are designed to appear, notwithstanding slip or variation in the web.

Mechanism of the kind is well known in the art. It includes various control devices by which the web-severing means is brought into operation in predetermined web length relation to a central control point in the path of travel of the web approximating or equaling the length of the labels or the distances between markings on said web. A control member, auxiliary or direct, associated with said control point in the path of the web, is operated upon by means on the web as it passes said control point, to affect the feed of the web beyond said control point to the position of the severing means.

Said control device may be actuated by mechanical engagement with the web or by light reflection or transmission from or through the web cast upon a light sensitive device, as a photo-electric cell, selenium cell or the like, or it may be a combination of the two. The control device is in circuit with electric conductors connected to an electro-magnet or motor which affects directly or indirectly the feed of the web. In some cases the intermittent feed of the web is accurately predetermined and exact for each web length severed, so that, for example, in the case of a web bearing labels, each severed label length when wrapped about the package for which it is designed, will be disposed in exact register with the faces of the package. In other cases, the control permits a certain tolerance of web under- or over-feed, which is corrected at predetermined intervals.

The mechanism illustrated herein and to which my improvement is applied is of the second named kind; but it involves no predetermination as to the intervals or as to the number of labels severed before correction is made. The control in this case depends entirely upon a predetermined aggregate of a minimum overfeed for each feeding operation before the permissible tolerance is exceeded, when correction is made. On account of the varying conditions of the web

as to contraction or expansion and the surrounding air temperature and moisture conditions and the like which affect the length of the web, the operation of the control device to effect the correction may, and generally does, occur at varying intervals of web feed and severance, sometimes including widely varying numbers of labels severed in successive intervals.

The object of the invention is to provide a releasable driving means for connecting a driving member and a driven member which is of simple and economical construction and which is readily and easily operated to permit a momentary lag of the driven member as and when determined by any suitable control member.

The objects and advantages of the invention will appear more fully as I proceed with the specification.

In the drawings:

Fig. 1 is a diagrammatic view, partly in section, of an apparatus embodying one form of the invention.

Fig. 2 is a top plan view of the feed and gripper and cutting rolls on an enlarged scale.

Fig. 3 is a fragmentary sectional view, on a still larger scale, of an escapement mechanism associated with the feed rolls, in a vertical plane indicated by the line 3—3 of Fig. 2.

Fig. 4 is a sectional view in a plane indicated by the line 4—4 of Fig. 3.

Fig. 5 is a like view with the parts shown in a different relation.

Fig. 6 shows a perspective view of the parts included in Fig. 3 as they appear in disassembled relation.

Referring now to that embodiment of the invention illustrated in the drawings:—10 indicates a web of any suitable material adapted for packages of predetermined dimensions, and bearing printed matter or other markings placed symmetrically upon successive, equal lengths into which the web is to be severed. Said web is fed in the usual manner in the direction of the arrows in Fig. 1 from a magazine roll (not shown). 11 and 12 indicate, respectively, upper and lower draft or feed rolls by means of which the web 10 is fed from the magazine roll. And 13 and 14 indicate correlated gripper and severing rolls,—the roll 13 bearing the knife or blade 13^a, and the roll 14 having a recess 14^a to receive the blade 13^a when it acts to sever the web. As shown, the roll 14 is designed to make two revolutions to one of the roll 13 in case the roll 13 is provided with an additional blade in the seat 55.

13^b diametrically opposite the blade 13^a, as when a label of shorter length is to be severed.

The feed of the web 10 as determined by the draft or feed rolls 11, 12 connected by the gears 11^x, 12^x (see Fig. 2), and the speed of the gripper and severing rolls 13 and 14 driven in definite geared relation thereto, is continuous in this case and is timed in relation to the operation of a wrapping or other device to which the severed 10 sections of the web are to be delivered. As shown in Fig. 2, the shaft of the lower gripper roll 14 has fixed to it a sprocket wheel 14^b which is connected by a sprocket chain 15 to a sprocket wheel 12^b on the shaft of the lower feed roll 12. At the 15 other end of the shaft of the lower gripper roll 14 is fixed a power-driven gear 14^x which engages a gear 13^x on the shaft of the gripper-severing roll 13.

So far the mechanism is old. In this case, however, the sprocket wheel 12^b is not fixedly connected to the shaft of the lower feed roll 12 as heretofore. It is indirectly connected thereto as will now be described. And in addition, the feed roll 12 is of such diameter that its circumference 25 is of a predetermined small amount in excess of the length of the labels or of the distance between the markings on the web 10. Thus each rotation of the feed roll 12 produces an over-feed of the web slightly in excess of the length of the 30 labels or of the distance between markings on said web.

Referring more specifically to Figs. 2 and 3, 17 indicates the shaft of the lower feed roll 12 at its end in proximity to the sprocket wheel 12^b which drives it, and 18, a frame member in which it has rotative bearing. 21 indicates a crank shaft coaxial with and spaced longitudinally from the end of the shaft 17. Said crank shaft, as shown in Fig. 2, is non-rotatively connected to 35 the armature shaft 23^a of an electric motor 23 by a connecting member 22. The electric motor 23 is mounted on bracket arms 23^b fixed to and extending from the frame member 18, with the armature shaft 23^a of said motor in coaxial 40 alignment with the crank shaft 21 and the shaft 17 of the feed roll 12.

26 indicates an internal escapement ring gear located in a plane between and concentric with the shaft 17 and the crank shaft 21. Said escapement gear is fixed between opposed, disc-like housing members 20, 24—the one, 20, rotatively mounted on the shaft 17, and the other, 24, rotative on the crank shaft 21. The housing member 20 has a hub 19 providing its bearing on the shaft 17, with an interposed bushing 17^a. The housing member 24 has a hub 24^a providing bearing of the crank shaft 21, with an interposed bushing 21^a. The housing member 20 has fixed to its hub 19 the sprocket wheel 12^b by a radial shoulder 19^a.

In the plane of the internal escapement ring gear 26 is located an escapement bar 31, which is reciprocable diametrically as to said escapement gear, and has teeth 31^a, 31^b at its ends for engagement therewith. (See Figs. 3, 4 and 5.) 65 32 indicates a bearing member having a groove 32^c (as more clearly shown in Fig. 6) in which said escapement bar is reciprocable. The bearing member 32 has a laterally extending stud 33 coaxial with the shaft 17 of the feed roll 12, said stud being engaged in a recess in the end of said shaft 17 and non-rotatively connected thereto by a lag screw 34 and interlocking key members 33^x, 17^x. (See Fig. 6.)

75 As more clearly shown in Fig. 6, the escape-

ment bar 31 is provided with a longitudinal recess 31^d which is closed on its open side by the bottom wall of the groove 32^c of the bearing member 32 to provide a housing for an expansion coil spring 31^e, located therein. A lug 32^b at one end of the 5 bearing groove 32^c engages an end of said coil spring, thus yieldingly holding the tooth 31^a at the far end of said escapement bar 31, as shown in Fig. 4, in engagement with the escapement ring gear 26. On its side adjacent to the crank 10 shaft 21, the said far end of the escapement bar 31 is connected by a pin 29 and a pitman 30 to said crank shaft.

With the parts as above described, and with the field of the electric motor 23 not energized, it is 15 obvious that power applied to drive the sprocket wheel 12^b will drive the housing composed of the members 20 and 24 with the escapement gear 26 gripped between them, the escapement bar 31 engaged therewith, and its bearing member 20 20 fixed to the shaft 17 of the feed roll 12. Thus said feed roll will be driven to feed the web 10, with the crank shaft 21 and the armature shaft 23^a of the electric motor 23 rotating idly with the shaft 17. As the crank shaft 21 is driven by the 25 escapement gear 26 and the escapement bar 31, it is obvious that there will be a slight advance in said crank shaft which will result in its having an off-center position with respect to said escapement bar as shown in Fig. 4.

If the crank shaft 21 be rotated through a small angle relatively to and in the direction of the rotation of the escapement gear 26 as indicated by the arrows in Figs. 4 and 5, said crank shaft will act through the pitman 30 to reciprocate the 35 escapement bar 31 longitudinally against the action of the expansion coil spring 31^e to disengage the tooth 31^a from its engagement with the escapement gear 26 and to bring the tooth 31^b at the other end of said bar into engagement 40 with said escapement gear as shown in Fig. 5. Upon discontinuance of the momentary impelling force which caused relative rotative movement of the crank shaft 21, the escapement bar 31 will be returned, by the expansion spring 31^e, to restore the pitman 30 and the crank shaft 21 to first position, the tooth 31^b being disengaged from escapement gear 26, and the tooth 31^a being reengaged with the next tooth of the escapement gear 26 45 back of the tooth previously engaged. As a result, there is a momentary lag in the rotation of the shaft 17 and of the feed roll 12.

The electric motor 23 is designed to impart the aforesaid momentary impulse by speeding up the rotation of the crank shaft 21 to relatively rotate 55 it through the angle required to operate the escapement bar as above described. The energizing of the field of said motor to impart said impulse is brought about by a control now to be described. It is shown diagrammatically in Fig. 1. 60

35 indicates a control unit of familiar construction. It includes a light-projecting device 36 adapted to project a light ray at a certain point 37 of the feed roll 12 upon the label or mark-bearing web 10 as it passes about said feed 65 roll. 38 indicates a light sensitive device, as a photoelectric cell, with associated amplifying means and electric conductors 38^a, 38^b in a relay circuit disposed to be affected by the light reflected from the web at the point 37 in a familiar 70 manner. 39, 40 indicate electric mains connected to the field of the electric motor 23. A relay 41 interposed in the relay circuit is controlled in the usual manner by the current through the amplifier associated with the photo- 75

electric cell. Said relay is adapted to close a normally open switch 41^a interposed in the main 39 connected to the field of the electric motor 23. 42 indicates a timer (see Figs. 1 and 2) mounted upon the shaft of the knife-bearing roll 13, and thus driven in synchronism with the gripping and cutting rolls. Said timer includes a rotor associated with suitable contacts interposed in the relay circuit and constituting a make-and-break switch 43. Each time the end of a label or marking on the web 10 passes the point 37 on the feed roll 12, the reflected light tends to affect the control device 38, but obviously no electric impulse may be imparted to the field of the motor 23 unless such reflection occurs in conjunction with the closing of the timer-operated switch 43. Then and then only will the relay 41 close the switch 41^a in the main circuit.

As I have shown, the length of web fed in each case is a small fraction in excess of the actual length of a label or distance between markings on the web. As a result, the lack of registration of the web lengths severed, with the labels or markings thereon, will increase more and more with each successive web length fed. After two or more labels have been severed, the lack of registration will reach an amount beyond which it is inadvisable to go. This amount represents the permitted tolerance, and is measured by the aggregate of overfeed for the number of labels fed before said tolerance is reached.

The timer switch 43 is set to operate in advance of the point 37 on the feed roll 12 by a distance measured on the web equal to the amount of said tolerance. As the overfeed of the web continues and aggregates, the advanced relation of the timer switch 43 to said point 37 diminishes for each successive feed of the web. When the predetermined tolerance has been absorbed, the timer switch 43 will close at the same time that the end of a label or marking on the web 10 interrupts the light to affect the control device 38, thus closing the relay circuit and causing the relay 41 to close the main circuit to the field of the electric motor. Thereupon the crank arm 21 is speeded up to operate the escapement bar to slip a tooth of the escapement gear 26 and engage the next one back of it, thereby momentarily retarding the feed roll 12 as heretofore described. The advance of the operation of the switch 43 with reference to the point 37 on the feed roll is thus restored, and the cycle is repeated. The number of labels severed before the limit of tolerance is reached may vary widely in different cycles.

While in describing the invention I have referred to many details of construction and of arrangement of parts, it is to be understood that the invention is in no way limited thereto, except as may be pointed out in the appended claims.

I claim as my invention:

1. A releasable driving means for connecting a housing and a feed roll comprising a gear and a diametrically reciprocable bar associated therewith, said gear having angular radial teeth and said bar having like teeth at each end, one of which is normally engaged in said gear and the other normally disengaged therefrom, a bearing member providing a recess for the reciprocation of said bar, said bearing member being mounted in said housing, being concentric with said feed roll and being connected to said feed roll, and means for reciprocating said bar to cause it to slip a tooth on said gear and permit a momentary lag of said feed roll.

2. A releasable driving means for connecting a driving member and a driven member comprising a gear and a diametrically reciprocable bar associated therewith, said gear having angular radial teeth and said bar having like teeth at each end, one of which is normally engaged in said gear and the other normally disengaged therefrom, a bearing member providing a recess for the reciprocation of said bar, a spring in said recess reacting between said bar and said bearing member to hold said bar engaged with said gear at one end, and means for reciprocating said bar to cause it to slip a tooth on said gear and permit a momentary lag of said driven member.

3. A releasable driving means for connecting a housing and a roll to be driven thereby, comprising a gear and a diametrically reciprocable bar associated therewith, said gear having angular radial internal teeth and said bar having like teeth at each end, one of which is normally engaged in said gear and the other normally disengaged therefrom, a bearing member providing a recess for the reciprocation of said bar, said bearing member being mounted in said housing concentrically with said feed roll and being rigidly connected to said feed roll, and means for reciprocating said bar to cause it to slip a tooth on said gear to permit a momentary lag of said feed roll.

4. A releasable driving means for connecting a housing and a rotative member driven thereby, comprising an internal escapement gear having angular radial teeth fixed in said housing and coaxial with said driven rotative member, a spring-actuated escapement bar having like radial teeth at its ends reciprocable in said housing and normally engaging said escapement gear, a bearing member providing a recess for the reciprocation of said escapement bar, said bearing member being mounted in said housing concentrically with said driven rotative member and being rigidly connected thereto, a crank shaft rotatively mounted in said housing, means connecting said crank shaft to said escapement bar, and means for actuating said crank shaft for reciprocating said escapement bar to cause it to slip a tooth to permit a momentary lag of said rotative driven member.

5. A releasable driving means for connecting a housing and a rotative member driven thereby, comprising an internal escapement gear having angular radial teeth in said housing and coaxial with said driven rotative member, an escapement bar having like radial teeth at its ends reciprocable in said housing and normally engaging said escapement gear, a bearing member providing a recess for the reciprocation of said escapement bar, said bearing member being mounted in said housing concentrically with said driven rotative member and being rigidly connected thereto, a spring housed in said escapement bar and reacting between said bar and said bearing member to hold said bar engaged with said gear at one end, a crank shaft rotatively mounted in said housing and connected to said escapement bar, and means for actuating said crank shaft for reciprocating said escapement bar to cause it to slip a tooth to permit a momentary lag of said rotative driven member.

6. A releasable driving means for connecting a driving member and a driven member, comprising a gear and a diametrically reciprocable bar associated therewith, said gear having angular radial teeth and said bar having like teeth at each end, one end of said bar being normally engaged with said gear and the other end of said

bar being normally disengaged from said gear, and means for reciprocating said bar to cause it to slip a tooth on said gear and permit a momentary lag of said driven member.

5. 7. A releasable driving means for connecting a driving member and a driven member, comprising a gear and a diametrically reciprocable spring-actuated bar associated therewith, said gear having angular radial teeth and said bar

having like teeth at each end, one end of said bar being normally engaged with said gear and the other end of said bar being normally disengaged from said gear, means for reciprocating said bar, and a control member for actuating said reciprocating means to cause said bar to slip a tooth on said gear and permit a momentary lag of said driven member.

WILLIAM RUSSELL REDD.
